UNITED STATES PATENT OFFICE.

FREDERICK G. MITCHELL, OF RIDGEFIELD PARK, NEW JERSEY, ASSIGNOR TO FAHNE-STOCK ELECTRIC COMPANY, OF LONG ISLAND CITY, NEW YORK, A CORPORATION OF WEST VIRGINIA.

SWITCH FOR B BATTERIES.

Application filed April 15, 1924. Serial No. 706,660.

To all whom it may concern:

Be it known that FREDERICK G. MITCHELL, citizen of the United States, residing at Ridgefield Park, in the county of Bergen and State of New Jersey, has invented certain new and useful Improvements in Switches for B Batteries, of which the following is a specification.

The present invention relates to switches for variable voltage batteries and consists in the combinations and arrangements of elements hereinafter described and particularly set forth in the accompanying claims.

With the use of the so-called B-batteries in radio, selective voltages are now obtained only by manually connecting the terminal wire with that binding post of the battery having the voltage desired, and this manipulation has the disadvantages of requiring both hands of the operator, prolonged interruption, and distraction. It is to overcome these faults that the device disclosed herein is proposed.

The invention, therefore, has for its purpose to provide a switch adapted to any type of B-battery used in radio wherein the different voltages may be selected in a quick, easy, and convenient manner and by a simple manipulation of the hand.

A further purpose of the invention is to provide a self contained switch of this character to the end that the same may be manufactured and sold as a single unit and adapted for ready attachment to any type of B-battery without in any way altering said battery or necessitating the use of separate attaching devices.

The invention is shown by way of illustration in the accompanying drawings wherein:

Figure 1 is a top plan view showing the switch applied to a type of B-battery;

Figure 2 a side elevational view thereof; and

Figure 3 a plan view of the switch per se.

Referring to the construction in further detail B designates any usual type of B-battery employed in radio having the several binding posts A adapted for selective connection with the conductor wire (not shown) through the threaded nuts C.

As above pointed out, the B-batteries now used in radio require direct attachment of the conductor wire with each of the binding posts A to obtain the particular voltage re-

quired, and which disadvantage the device herein shown is designed to overcome.

The switch per se, as an article of manufacture, consists of a base piece or support 4 of suitable non-conductive material preferably fibre, and having thereon a plurality of radially arranged connective members or arms 5, each pivotally mounted on the base piece 4 as at 6, and said arms are of suitable conductive metal. A slot 7 extending substantially the full length of each arm adapts the device to be adjustably fitted and secured to the several binding posts A, of any B-battery, and when so applied, said arms are secured through the several nuts C as shown. The angular and radial adjustment features of the device readily adapts the switch for ready application to B-batteries quite regardless of the relative distance and arrangement of its binding posts.

The contact maker consists of a member 8 pivoted at 9 on the plate 4 and having an inturned end 10 adapted to have conductive contact with the portions 11 of the several arms 5 as shown. A suitable terminal clip F preferably a Fahnestock clip, is secured to the free end 12 of the arm 8 and serves to move the contact maker for selecting different voltages and for connecting with the wire completing the circuit.

It is to be understood that I do not desire to limit myself to the precise details of construction and arrangement herein set forth, as it is obvious that various modifications may be made therein without departing from the essential features of the invention.

What is claimed as new is:-

1. A switch for electric batteries having binding posts comprising a non-conductive base, connecting elements pivotally assembled on said base and radially adjustable on the binding posts, and a contact maker adapted to selectively connect with any one of said connecting elements.

2. A switch for electric batteries comprising a plurality of pivotally assembled contact arms radially slotted for battery connections, and a selective contact maker.

3. The combination with a battery having binding posts of connecting elements providing radially adjustable contacts for the binding posts, and a contact maker adapted to selectively connect with any one of said connecting elements.

4. A switch for batteries having binding

posts, comprising a non-conductive base, contact arms adapted for radial adjustment with said binding posts, and a selective contact maker having a lip for contacting with said arms, said contact maker and arms being pivotally mounted on the base.

5. A switch for batteries having binding posts, comprising contact arms angularly and radially adjustable with regard to the 10 binding posts, a selective contact maker for

said contact arms, and a non-conductive, common base for said arms and contact maker.

6. A switch for batteries comprising a plurality of pivotally assembled contact members having slots for battery connections, and a pivotal selective contact maker.

In testimony whereof I affix my signature.

FREDERICK G. MITCHELL.
